No. 708,975.

Patented Sept. 9, 1902.

C. E. GLAFKE.

BAKER'S OVEN.

(Application filed Aug. 2, 1901.)

(No Model.)

UNITED STATES PATENT OFFICE.

CHARLES E. GLAFKE, OF LOS ANGELES, CALIFORNIA.

BAKER'S OVEN.

SPECIFICATION forming part of Letters Patent No. 708,975, dated September 9, 1902.

Application filed August 2, 1901. Serial No. 70,645. (No model.)

To all whom it may concern:

Be it known that I, CHARLES E. GLAFKE, a citizen of the United States, residing at Los Angeles, in the county of Los Angeles, State 5 of California, have invented new and useful Improvements in Bakers' Ovens, of which the following is a specification.

My invention relates, primarily, to that class of bakers' ovens commonly called "reel-ovens," in which the material to be baked is placed on swinging pans or shelves suspended from the arms of a reel within a baking-chamber supplied with the products of combustion from a furnace or flues in the lower part 15 of the baking-chamber, the reel being rotated as required to bring the swinging shelves in turn to the mouth of the oven to be discharged and recharged by the ovensman; and the object thereof is to provide a furnace in 20 which hydrocarbon fuel or gaseous fuel may be used to produce the required heat for baking.

In the accompanying drawings, which illustrate my invention as applied to the form of 25 reel-oven mechanism in common use, Figure 1 is a perspective view of my improved oven with a part of the front broken away. Fig. 2 is a section taken on the line 2 2 of Fig. 1 with a part of the reel removed. Fig. 30 3 is a section on the line 3 3 of Fig. 2.

In the drawings, A is the oven, having chimney B to produce a draft to carry off any smoke which may be generated in starting the fires.

35 C is the baking-chamber, in the upper portion of which is reel D, which carries the swinging shelves or pans E, which support the material while it is being baked. F is the door, which permits of the insertion and 40 removal of said material from the shelves. In the bottom portion of the baking-chamber is the main flue G, the front part of which forms a combustion-chamber which preferably extends across the baking-chamber. The 45 rear portion is preferably contracted and is connected with the chimney, the opening therebetween being controlled by chimney-damper H, which is operated by rod I. Near the rear portion on each side of the 50 main flue and in communication therewith are connected thereto auxiliary flues J and K, which terminate in open ends a short dis-

tance from the front wall of the oven. The ends of these auxiliary flues that are nearer the front wall of the oven are provided with 55 auxiliary-flue dampers L and M, which are operated by rods N and O. Projecting into the front portion of the main flue is hydrocarbon-burner P, connected to a suitable fuel and steam supply, (not shown,) below which is 60 main-flue damper R, operated by rod S, by means of which the amount of air admitted into the flue is controlled. This main flue could be located to one side of the center of the baking-chamber and used with only one 65 auxiliary flue. I prefer the central position and the use of two auxiliary flues, as that arrangement distributes the heat better than with one auxiliary flue.

In the operation of my oven suitable fuel, 70 such as distillate or crude petroleum and steam or gaseous fuel, is supplied to the burner and the fire is lighted, the oven-door and the auxiliary-flue dampers are closed, and the main flue and the chimney-dampers are 75 opened sufficiently to produce a good draft up the chimney. As soon as the main flue is sufficiently heated the chimney-damper is closed and the auxiliary-flue dampers and the oven-door are opened. This causes the 80 products of combustion to enter the baking-chamber through the auxiliary flues and to pass out at the oven-door, which soon raises the temperature of the baking-chamber to the baking-point, when the material to be baked 85 is put upon the shelves of the reel, which is slowly rotated in the direction of the arrow. It will be observed that by joining the auxiliary flues to the main flue near the back of the oven and by leading them away from the 90 main flue and toward and terminating near the front of the oven the heat has to travel to the back of the oven in the main flue and then to near the front of the oven in the auxiliary flues, thereby evenly distributing the 95 heat-radiating surfaces over the bottom of the oven, and the heat will be radiated from the top and sides of the main and auxiliary flues, and that a portion of the heat passes out of the open ends of the auxiliary flues and passes 100 up and out of the oven-door. It will also be observed that the material to be baked passes down through the escaping heated products of combustion and that the bottom thereof is

first presented thereto, causing the material to be first baked on the bottom. The distance which the products of combustion have to travel in the main and auxiliary flues 5 causes their complete and perfect combustion in the flues, so that no smoke or objectionable gases escape into the baking-chamber, thereby rendering it possible to use the oven continuously instead of intermittently, as is 10 the case with all ovens with which I am acquainted.

In all the reel-ovens with which I am acquainted coal, coke, wood, or other similar fuel is used in furnaces placed at the front 15 of and under the floor of the baking-chamber. Sometimes these furnaces are so arranged that after the fire has been started and the fuel has reached the incandescent state by means of openings and auxiliary flues the 20 furnace-chamber is put in communication with the baking-chamber, and the products of combustion pass directly into the baking-chamber; but such ovens are not adapted for the use of liquid hydrocarbon fuel, and the 25 ordinary fuel must be used. As soon as the incandescent fuel in the furnace is consumed or has parted with most of its heat the direct communication with the baking-chamber must be closed and new fuel put into the fur- 30 nace and the usual draft opened until the new fuel reaches the incandescent state, when direct communication with the baking-chamber may be again established. This operation renders the efficient baking effect of the 35 oven intermittent.

Having thus described my invention, what I claim as new, and desire to secure by Letters Patent, is—

1. In a reel-oven, a flue in the lower portion 40 of the baking-chamber, extending therethrough to and communicating with the chimney; a damper in the opening between the flue and chimney; a branch flue in communication with the main flue near the chimney, and extending away from and terminating 45 near the front wall of the oven, in an open end; a damper in the open end of the branch flue and a door in the front wall of the oven above the said flues, whereby the 50 products of combustion pass through the main flue, then into the auxiliary flue and out thereof up through the oven and out of the door thereof.

2. In combination with a reel-oven, a flue 55 in the bottom of the oven extending therethrough transversely to the axis of the reel

and communicating with the chimney; a damper in the opening between the flue and chimney; a branch flue communicating with the main flue near the chimney, on each side 60 thereof, extending away therefrom, and toward, and terminating in an open end near the front wall of the oven; a damper in the open ends of the branch flues, and a hydrocarbon-burner in the front end of the main 65 flue and a door in the front wall of the oven above the said flues, whereby the products of combustion pass through the main flue, then into the auxiliary flue and out thereof up through the oven and out of the door 70 thereof.

3. In a reel-oven, a main flue in the bottom of the baking-chamber, extending therethrough, in communication with the chimney and having the front portion adapted for a 75 combustion-chamber; a damper adapted to control the communication between the flue and chimney; branch flues in communication with the main flue, near the chimney and extending away from, and toward, and terminating in open ends near the front wall of the oven; dampers in, and adapted to control the open ends of the branch flues and a door in the front wall of the oven above the said flues, whereby the products of combustion 80 pass through the main flue, then into the auxiliary flue and out thereof up through the oven and out of the door thereof.

4. In a reel-oven, a main flue in communication with the chimney, having its front end 90 adapted for a combustion-chamber; a branch flue in communication with the main flue near the chimney, extending away from said flue, and terminating in an open end near the front of the oven; a damper in the main flue, 95 controlling the opening therefrom into the chimney; a damper in the branch flue controlling its open end, and a door in the front wall of the oven above the said flues, whereby the products of combustion pass through 100 the main flue, then into the auxiliary flue and out thereof up through the oven and out of the door thereof in combination with a hydrocarbon-burner in the combustion-chamber of the main flue.

In witness that I claim the foregoing I have hereunto subscribed my name this 26th day of July, 1901.

CHARLES E. GLAFKE.
